UNITED STATES PATENT OFFICE

ROSE OLANS, OF NEW YORK, N. Y.

DESIGN FOR A CLIP

Application filed March 5, 1932. Serial No. 43,087. Term of patent 7 years.

To all whom it may concern:

Be it known that I, ROSE OLANS, a citizen of the United States of America, residing in New York city, county of New York, State of New York, have invented a new, original, and ornamental Design for a Clip, of which the following is a specification, reference being had to the accompanying drawings, forming a part thereof.

Fig. 1 is a face view of a clip showing my new design; and Fig. 2 is a side elevation of the same.

I claim:

The ornamental design for a clip, substantially as shown.

ROSE OLANS,
